(Continued)

The ornamental design for a rear portion of a percussive high frequency chest wall oscillation system, as shown and described.

(51) **LOC (13) Cl.** **28-03**

DESCRIPTION

(52) **U.S. Cl.**

FIG. 1 is a front perspective view of a rear portion of a
percussive high frequency chest wall oscillation system in
accordance with the present design;

USPC **D24/200**

FIG. 2 is a front elevation view thereof;

(58) **Field of Classification Search**

FIG. 3 is a rear elevation view thereof;

USPC D24/200, 107, 164; D2/828-829

FIG. 4 is a right side elevation view thereof;

CPC A61H 9/00; A61H 9/005; A61H 9/0007;

FIG. 5 is left side elevation view thereof;

A61H 9/0071; A61H 9/0078; A61H

FIG. 6 is a top plan view thereof; and,

7/004; A61H 23/00; A61H 23/006; A61H

FIG. 7 is a bottom plan view thereof.

(Continued)

The broken lines depict portions of the rear portion of the percussive high frequency chest wall oscillation system and form no part of the claimed design.
